Primary Examiner—Melody N. Brown**[57] CLAIM**

The ornamental design for insert and channel auto windshield molding, as shown and described.

DESCRIPTION

FIG. 1 is a perspective view of insert and channel auto windshield molding showing my new design;

FIG. 2 is a front elevational view thereof;

FIG. 3 is a rear elevational view thereof;

FIG. 4 is a bottom view thereof;

FIG. 5 is a top view thereof;

FIG. 6 is a right end elevational view thereof; and,

FIG. 7 is a left end elevational view thereof.

The end of the molding is shown broken away in FIGS. 1-5 to indicate indeterminate length.
